SHORE

Albert Negovan, Chicago, Ill., and Estel R. Stratton and William Clark Roggie, Indianapolis, Ind., assignors to Baker-Roos, Inc., Indianapolis, Ind., a corporation of Indiana

Application August 6, 1943, Serial No. 497,674

10 Claims. (Cl. 248—354)

1

Our invention relates to adjustable shores, and more particularly to that type of shore in which one of two telescoping parts comprises a pair of laterally spaced, longitudinally extending members between which the other shore-part is adjustably received.

It is the object of our invention to produce for such a shore a removable extension by the use of which the effective length of the shore can be increased. More specifically, it is our object to interconnect the shore and extension by a means which will hold the extension firmly in alignment with the shore without requiring an excessive amount of longitudinal overlapping of the extension and shore. A further object of our invention is to adapt a shore not only for the reception of an extension but also for the reception of an auxiliary head by means of which the area which the shore affords for the support of objects resting upon it may be materially increased.

In carrying out our invention, we provide the two-member shore-part, which is usually used as the upper part of the shore, with a cap which serves not only to hold in properly spaced relation the upper ends of the two members of which the upper short-part is composed but which also serves to receive the lower end of a shore-extension. The cap and shore-extension are provided with interfitting means which serve to hold the shore-part and extension firmly in alignment with each other. The cap is so formed as not to interfere with the usual use of the shore in the absence of the extension, and is desirably also formed to receive a head of increased width.

The accompanying drawing illustrates our invention:

Fig. 1 is a side elevation of the complete shore with the extension in place thereon; Fig. 2 is a fragmental isometric view illustrating the upper end of the shore; Fig. 3 is an isometric view illustrating the lower end of the shore-extension; Fig. 4 is a plan view of the upper end of the shore showing, in section, the lower end of the extension in place therein; Fig. 5 is a vertical section through the upper end of the shore and extension; and Fig. 6 is a fragmental side elevation illustrating the auxiliary head in place on the shore.

The shore illustrated in the drawing comprises a lower part 10 formed of pipe and provided with a suitable foot 10'. The upper part of the shore comprises two laterally spaced vertically extending members 11, which may be wood 2 x 4's. The upper end of the pipe 10 is provided with a cross-

2

head 12 slidably engaging the members 11, while the lower ends of the latter are provided with co-operating dogs 13 adapted to grip the pipe 10 and hold the shore extended under load. The construction of the lower shore part and the dogs 13 forms no part of our invention.

The upper ends of the two members 11 are held in spaced relation by a cap 15, the particular construction of which does form part of our invention. As will be clear from Fig. 2, the cap 15 embodies co-planar end portions 16 which overlie the upper ends of the shore-members 11. The central portion of the cap is in the form of a stirrup, comprising two vertical side walls 17 which extend downwardly along the inner faces of the members 11 and the lower ends of which are joined by a horizontally extending intermediate or bottom wall 18. Desirably, the cap also includes strengthening flanges 19 which extend vertically downward from the side edges of the end portion 16 and which bridge the gap between the two members 11. The cap may be formed as a casting, or may be constructed by welding together pieces of properly shaped steel plate. Bolts 20, which pass through the vertical legs 17 and the respectively adjacent members 11, serve to hold the cap in place.

The extension 22 for use with the shore may be of any desired length and conveniently comprises a wood 4 x 4. The lower end of the extension 22 is reduced in both transverse dimensions so that it may be received within a hollow sleeve 23 which desirably has the same exterior dimensions as those of the body of the shore-extension.

The cap 15 is so proportioned that the sleeve 23 may be received between the two side walls 17 and flanges 19 of the cap; and the sleeve and cap are provided with interengaging portions by means of which the extension is held in proper alignment with the shore. As shown, such provisions include tongues 25, which are secured (as by welding) to two opposite sides of the sleeve 23 and which are receivable in grooves 26 formed in the side walls 17 of the cap. The interengaging faces of the tongues 25 and grooves 26 may converge downwardly slightly, so as to produce a taper fit which will become tight when the extension is seated in the shore. In addition, the other two sides of the sleeve 23 are provided with downwardly projecting ears 27 receivable in notches 28 formed in the sides of the bottom wall 18 of the cap. Desirably, the key-receiving grooves 26 of the cap are slots extending completely through the material of the side walls 17 and continuing into the intermediate leg 18 to

receive the lower ends of the tongues, which project below the lower end of the sleeve 23. To prevent injury to the wood shore-members 11 when the extension is being inserted, the end and inner face of each of such members may be protected by an L-shaped sheet-metal protector 39 interposed between the member and the cap.

By providing the lower end of the shore extension with the metal sleeve 23, and by forming the sleeve-receiving portion of the cap 15 of metal, we are enabled to obtain a relatively snug fit between the cap and sleeve, whereby the extension will be held firmly in proper alignment with the shore. Moreover, the fit of the tongues 25 within the slots 26, and the fit of the ears 27 within the notches 28 aid in preventing relatively lateral movement of the shore and the extension, and thus aid in maintaining those elements in proper alignment with each other.

For the purpose of releasably holding the extension in association with the shore the flanges 19 may be provided with small openings 31 which, when the extension is in place, are in alignment with openings 32 provided in opposite side walls of the sleeve 23, whereby a nail driven into the wood of the extension-shank 22 through the openings 31 and 32 will prevent the extension from being removed from the shore.

In order to provide an adequate supporting surface for any object supported by the shore when the extension is not in use the end portions 16 of the cap 15 desirably extend outwardly for a distance beyond the outer faces of the members 11, as will be clear from the drawing. In the absence of the extension 22, objects may be supported on the upper surfaces of the end portions 16 and the upper edges of the flanges 19, which are all coplanar.

The cap 15 is adapted for the reception of any desired form of laterally projecting auxiliary head, such for example as the plain auxiliary head 35 illustrated in Fig. 6. This auxiliary head conveniently comprises a length of 3 x 4 or 4 x 4 to the lower surface of which there is secured a metal clip 36 adapted to engage the projecting end of either of the end portions 16 of the shore-cap. Also secured to the under surface of the head 35 is an L-shaped member 37 one leg of which is vertical and adapted to extend through a slot 38 in the other of the end portions 16 of the shore-cap. A removable key 39 receivable in a hole in such member may be employed to hold the head 35 releasably in place.

The lower end of the extension 22 is preferably flush with, or even slightly below, the lower end face of the sleeve 23 so that when the extension is in use its lower end will engage the bottom wall 18 of the extension-receiving stirrup, whereby vertical loads will be transmitted directly from the extension to the cap independently of the sleeve.

While we have illustrated and described the shore as vertically arranged with the short-part comprising the members 11 uppermost, it is to be understood that this is merely for convenience of description. The shore can be inverted if desired, or it can be used in a horizontal or inclined position.

We claim as our invention:

1. In a shore having upper and lower telescoping parts, said upper part comprising two laterally spaced, vertically extending members, a cap having end portions respectively overlying the ends of said members and flanges interconnecting said end portions and extending across

the space between said members at opposite sides thereof, said cap being provided with a central stirrup extending downwardly between said two members and said flanges and having side and bottom walls, a shore-extension, and a sleeve upon the lower end of said extension, said sleeve being adapted to be received in said stirrup and between said flanges, opposite sides of said sleeve and the side walls of said stirrup being provided with closely interfitting, longitudinally extending tongues and grooves preventing relative movement of said sleeve and stirrup in a plane perpendicular to said flanges.

2. In a shore having upper and lower telescoping parts, said upper part comprising two laterally spaced, vertically extending members, a cap having end portions respectively overlying the ends of said members and flanges interconnecting end portions and extending across the space between said members at opposite sides thereof, said cap being provided with a central stirrup extending downwardly between said two members and said flanges and having side and bottom walls, a shore-extension having a lower end adapted to be received in said stirrup and between said flanges, opposite sides of said extension and the side walls of said stirrup being provided with closely interfitting, longitudinally extending tongues and grooves preventing relative movement of said extension and stirrup in a plane perpendicular to said flanges.

3. The invention set forth in claim 1 with the addition that said tongues are tapered and of gradually decreasing width downwardly, the tongue-receiving grooves being correspondingly tapered.

4. The invention set forth in claim 2 with the addition that said tongues are tapered and of gradually decreasing width downwardly, the tongue-receiving grooves being correspondingly tapered.

5. The invention set forth in claim 1 with the addition that said grooves are located in the side walls of said stirrup, and bolts passing through each stirrup side wall on opposite sides of the groove therein and also through the adjacent vertically extending member of the upper shore-part.

6. The invention set forth in claim 2 with the addition that said grooves are located in the side walls of said stirrup, and bolts passing through each stirrup side wall on opposite sides of the groove therein and also through the adjacent vertically extending member of the upper shore-part.

7. In a shore, upper and lower telescoping parts, a centrally disposed, upwardly opening stirrup at the upper end of said upper shore-part, said stirrup having spaced, parallel side walls, an extension receivable in said stirrup between said side walls, said side walls and the adjacent faces of said extension being provided with closely interfitting, longitudinally extending tongues and grooves preventing relative movement of said extension and stirrup in a plane parallel to said side walls of the stirrup.

8. The invention set forth in claim 7 with the addition that said tongues are tapered and of gradually decreasing width downwardly, the tongue-receiving grooves being correspondingly tapered.

9. In a shore, upper and lower telescoping parts, a centrally disposed, upwardly opening stirrup at the upper end of said upper shore-part, said stirrup having spaced, parallel side walls and

a bottom wall, an extension adapted to be received in said stirrup with its lower end supported on said bottom wall, the lower end of said extension and said bottom wall having closely interfitting provisions preventing their relative lateral movement.

10. The invention set forth in claim 9 with the addition of a rigid sleeve surrounding the lower

end of said extension, said interfitting provisions comprising downwardly extending projections on said sleeve and projection-receiving openings in said bottom wall.
